AUTOMATICALLY-THREADING LOOM SHUTTLE

Application filed December 27, 1929. Serial No. 416,776.

This invention relates to automatically threading loom shuttles and is more particularly directed to the means for applying tension of desired character to the thread during weaving.

Automatically threading loom shuttles are now ordinarily employed in what are known as "feeler looms" whereby the filling carrier in the shuttle is changed from time to time and the shuttle becomes automatically threaded during its picking movements.

Some character of tensioning means has heretofore been employed in shuttles of the automatically threading type, and the present invention is directed to a thread tensioning device which shall present tensioning members located at the front portion of the usual longitudinal thread passage so that on the first pick of the shuttle following replenishment the thread will pass into control of the tensioning members and be thereafter subjected to uniform tension throughout the weaving operation.

More specifically stated, the invention comprises a thread tensioning post preferably mounted in the threading block at the point where the longitudinal thread passage communicates with the side delivery eye, and cooperating with the thread tensioning post is a tensioning plate normally under the influence of a spring tending to move the plate into tensioning relation with the post. A tensioning device of the general character stated is particularly advantageous where the lower wall of the thread passage is lower than usual, and in order to insure that the thread may not drop out of control of the tensioning members during weaving, the tensioning surfaces of said members extend downwardly beyond the lower wall of the thread passage.

The invention and novel features thereof will best be made clear from the following description and the accompanying drawings of one good, practical form thereof.

In the drawings:

Fig. 1 is a plan view of the delivery end portion of an automatically threading shuttle provided with the present invention;

Fig. 2 is a perspective view, with parts of

the threading block broken away to show more clearly the relation of the tensioning members and longitudinal thread passage;

Fig. 3 is a side elevation of the threading block detached from the shuttle and showing some parts in section; and

Fig. 4 is a perspective view of the threading block detached from the shuttle, some of the parts broken away, and the lead of the filling thread as it passes around the tensioning post towards the side delivery eye.

The shuttle 1 is provided with the usual bobbin chamber 2 and the side delivery eye 3 from which the filling thread *a* leads during weaving as it is withdrawn from the filling carrier of bobbin 4. Frontward of the bobbin chamber the shuttle is provided with the threading block 5 having a longitudinally extending thread passage 6 and an open top portion 7 through which the thread passes into the longitudinal thread passage on replenishment of filling. The threading block has the thread director 8 between the front edge portion of which and a cut-away portion 9 of the shuttle there is an opening for the thread to pass to the side delivery eye on the second pick of the shuttle following replenishment, and overhanging the end portion of the thread director 8 is a guard 10. As thus far described the threading block may be of usual construction and is held in the shuttle by the through bolt 11 as usual. Extending downwardly from the threading block is the lug or pin 12 which engages the usual opening in the shuttle for assisting in positioning the threading block.

Mounted in the threading block at the point of communication between the longitudinal thread passage 6 and the passage leading to the side delivery eye is a thread tensioning post 13 which may be secured to the threading block in any appropriate manner, but as herein shown, the post 13 has a slot 14 which is engaged by a pin 15 which extends from the lower portion of the post upwardly and is secured in the side of the threading block adjacent the side delivery eye, as at 16, Fig. 2, the result being that the threading post 13 is held in fixed position beyond the forward end of the thread passage and the

lower portion of the post extends downwardly beyond the lower wall 17 of the thread passage 6, as indicated in Fig. 2. The threading post 13 may be formed of suitable material, such, for instance, as a vitreous substance, or, 5 it may, on the other hand, be formed of metal, the essentials in this respect being that it shall be positioned to direct the thread from the longitudinal thread passage to the side delivery eye.

10 As hereinbefore indicated, the longitudinal thread passage of the threading block is formed as a low groove and at the front portion the threading block is cut away, at 18, 15 and from the cut-away portion a pin 19 extends frontwardly to provide an anchoring means for the tensioning plate. The tensioning plate 20 is disposed opposite the tensioning post 13 and has an extended vertical thread engaging face which extends below the lower wall 17 of the longitudinal thread passage where it is turned outwardly and provided with a loop 21 which is engaged by the pin 19, and to prevent the thread tensioning plate from disengagement from the 20 pin 19 the latter is provided with a head 22, the construction being such that the thread tensioning plate 20 is mounted for movement towards and from the thread tensioning post.

25 The upper portion of the thread tensioning plate is turned outwardly at 23 and the end of the turned-out portion 23 enters a slot 24 formed in the side wall of the longitudinal thread passage, at the front portion thereof, with the result that when the thread passes downwardly into the thread passage of the threading block it will be directed between the thread tensioning plate and thread tensioning post, as indicated in Figs. 2 and 4.

30 The thread tensioning plate is normally 40 under the influence of a spring tending to move the tensioning plate into tensioning relation with the tensioning post, and, as indicated in the present instance of the invention, the spring is of the leaf type, or formed 45 as a flat spring plate, the rear portion of which at 25 is turned about the rear wall 26 of the threading block into loop form, and the outer portion thereof is secured to the 50 threading block by a pin 27 which passes through the wood of the shuttle and through the wall 26 of the threading block.

55 Within the longitudinal thread passage the spring is turned frontwardly at 28 and has an arm 29 extending longitudinally in the thread passage with its forward end bearing upon the outside surface of the tensioning plate 20, with the result that the tensioning plate is normally spring-stressed towards the 60 tensioning post.

65 In weaving with different kinds of filling thread it is desirable to vary the tensioning effect of the frontwardly extending arm of the spring upon the tensioning plate, to thereby vary the tension exerted upon the filling

70 thread, and to this end the pin 27 has a threaded portion 30 engaging a corresponding thread in the side wall 26 of the threading block, so that by turning movement of the pin 27 the tension of the spring arm 28 may be varied.

75 During the weaving operation the shuttle is subjected to sudden shocks and impulses, as well known, and to prevent disturbance of spring adjustment the pin 27 has a flattened or hexagonal portion 31 against which bears the upper portion of a flattened spring 32, the lower end of which is secured to a projection 33 of the threading block. The tension of the flattened spring 32 is sufficient to maintain the pin 27 from rotative movement under the varying shocks to which the shuttle is subjected but is yieldable, nevertheless, to permit manual turning of the pin in varying the tension of the spring.

80 From the construction described it will be obvious that the present invention provides an automatically threading loom shuttle with a thread tensioning post at the point of communication between the side delivery 85 eye and the longitudinal thread passage and a cooperating thread tensioning plate between which and the post the thread is tensioned during weaving, and both the lower end of the thread tensioning post and the lower portion of the thread tensioning plate extend below the lower wall 6 of the longitudinal thread passage, so that all danger of the thread passing below and out of control of the tensioning members is avoided. It 90 will also be noted that the spring arm 28 extends in the longitudinal thread passage frontwardly and that its end bears against the thread tensioning plate, and the tension of the spring arm by the pin 27 will remain constant during weaving owing to the hexagonal portion 31 of the pin and the yielding plate 32.

95 What is claimed is:

100 1. An automatically threading loom shuttle having a longitudinal thread passage and a side delivery eye communicating therewith that the shuttle may be automatically threaded, a thread tensioning post mounted at the point of communication between the side delivery eye and longitudinal passage, a tensioning plate supported independently of the post at the side of the thread passage opposite the tensioning post, a spring secured at the rear of the thread passage so that it is supported independently of said plate and having a forwardly extending portion bearing upon the tensioning plate that the thread may be tensioned between the post and plate as it passes about the post to the side delivery eye.

105 2. An automatically threading loom shuttle having a threading block provided with a longitudinal thread passage, a side delivery eye, a thread tensioning post about which

the thread passes to the side delivery eye, an upright tensioning plate frontward of the lower wall of the longitudinal passage of the threading block and mounted for movement 5 towards and from the thread tensioning post and provided with end portions that extend laterally of the block away from said post, and a spring normally acting to move the tensioning plate toward the post that the 10 thread may be tensioned as it passes about the post to the side delivery eye.

3. An automatically threading loom shuttle having a threading block provided with a longitudinal thread passage, a side delivery 15 eye communicating with the longitudinal thread passage that the shuttle may be automatically threaded, a thread tensioning post frontward of the longitudinal passage formed in the threading block, a tensioning plate 20 mounted on the threading block frontward of its longitudinal passage for movement bodily relative to said post and extending below the bottom wall of said passage opposite the tensioning post for movement towards 25 and from the post, and a spring normally acting upon the plate to move it towards the post that the thread may be tensioned as it passes about the post to the side delivery eye.

4. An automatically threading loom shuttle having a threading block provided with a longitudinal thread passage, a side delivery eye, a thread tensioning post frontward of the lower wall of the thread passage, a tensioning plate also frontward of the lower 35 wall of the thread passage formed in the threading block and provided with a loop, a projection extending frontward of the threading block within said loop to form a sliding engagement therewith, and a spring 40 normally acting to move the tensioning plate towards the post that the thread may be tensioned frontward of the lower wall of the thread passage as it passes about the post to the side delivery eye.

45 5. An automatically threading loom shuttle having a threading block provided with a longitudinal thread passage, a side delivery eye, a thread tensioning post frontward of the lower wall of the thread passage, a tensioning plate also frontward of the lower wall 50 of the thread passage formed in the threading block and provided with a loop, a projection extending frontward of the threading block and loosely engaging said loop and having a head to prevent disengagement of the tension plate from the projection, and a spring normally acting to move the tensioning plate towards the post that the thread 55 may be tensioned frontward of the lower wall of the thread passage as it passes about the post to the side delivery eye.

60 6. An automatically threading loom shuttle having a longitudinal thread passage and a side delivery eye communicating therewith 65 that the shuttle may be automatically thread-

ed, a thread tensioning post mounted at the point of communication between the side delivery eye and longitudinal passage, a tensioning plate mounted at the side of the thread passage opposite the tensioning post, 70 a leaf spring supported independently of the tension plate and secured at the rear of the threading block and having a frontwardly extending arm bearing upon the tensioning plate that the thread may be tensioned between the post and the plate as it 75 passes about the post to the side delivery eye.

7. An automatically threading loom shuttle having a threading block provided with a longitudinally extending thread passage 80 and a side delivery eye, a tensioning post at the front of the longitudinal thread passage, a tensioning plate opposite the post, a leaf spring having a loop secured to the rear of the threading block and having a frontwardly extending portion bearing upon the tensioning plate, means for supporting the tension plate independently of the leaf spring, and an adjusting screw bearing upon the frontwardly extending portion of the 85 spring.

8. An automatically threading loom shuttle having a threading block provided with a longitudinally extending thread passage and a side delivery eye, a tensioning post at the front of the longitudinal thread passage, a tensioning plate opposite the post, a leaf spring having a loop secured to the rear of the threading block and having a frontwardly extending portion bearing upon the 90 tensioning plate, an adjusting screw bearing upon the frontwardly extending portion of the spring and having a flattened locking portion, and a yielding finger adapted to bear upon the said flattened portion to 100 prevent accidental disturbance of the spring adjustment due to the shuttle movements. 105

9. An automatically threading loom shuttle having a longitudinal thread passage and a side delivery eye communicating therewith, a thread tensioning post rigidly mounted at the point of communication between the side delivery eye and longitudinal thread passage, a tensioning plate slidably mounted opposite said post at its top and bottom to present a vertical surface to bear flatwise against the fixed tensioning post, and a leaf spring having a forwardly extending arm to bear upon the back of the tensioning plate that the thread may be evenly tensioned between the post and tensioning plate as it passes about the post to the side delivery eye. 110 115 120

10. An automatically threading loom shuttle having a longitudinal thread passage and a side delivery eye communicating therewith, a thread tensioning post rigidly mounted at the point of communication between the side delivery eye and longitudinal thread passage, a tensioning plate protec- 125 130

tively mounted opposite said post at its top and bottom for sliding movement towards and from the tensioning post to prevent the thread from passing back of the tensioning plate during shuttle threading and a leaf spring having a forwardly extending arm bearing centrally on the back of the tensioning plate that the thread may be evenly tensioned between the post and plate as it passes about the post to the side delivery eye.

10 11. An automatically threading loom shuttle having a longitudinal thread passage and a side delivery eye communicating therewith, a thread tensioning post mounted at the point of communication between the side delivery eye and longitudinal passage, a tensioning plate protectively mounted in a vertical position opposite said post for sliding movement towards the tensioning post to present a surface to bear flatwise against the tensioning post where the thread passes about the post to the side delivery eye and provided with end portions that extend away from the post, and a spring normally acting to move the tensioning plate into bearing relation against the post that the thread may be evenly tensioned between the post and plate as it passes about the post to the side delivery eye.

20 In testimony whereof, I have signed my name to this specification.

HARRY A. DAVIS.
